UNITED STATES PATENT OFFICE

137,302

DESIGN FOR A THERMOMETER CASE OR SIMILAR ARTICLE

Donald E. Dailey, Philadelphia, Pa., assignor to
Manning, Maxwell & Moore, Incorporated,
New York, N. Y., a corporation of New Jersey

Application November 4, 1943, Serial No. 111,599

Term of patent 14 years

To all whom it may concern:

Be it known that I, Donald E. Dailey, a citizen of the United States of America, residing in Philadelphia, in the county of Montgomery and Commonwealth of Pennsylvania, have invented a new, original, and ornamental Design for a Thermometer Case or Similar Article, of which the following is a specification, reference being had to the accompanying drawing forming a part thereof.

Fig. 1 is a front elevational view of a thermometer case showing my new design;

Fig. 2 is a side elevation of the case; and
Fig. 3 is a plan view of the case.

I claim:

The ornamental design for a thermometer case or similar article, substantially as shown.

DONALD E. DAILEY.
